[57] CLAIM

The ornamental design for a pyrotechnic rocket, as shown and described.

DESCRIPTION

FIG. 1 is a front elevational view of a pyrotechnic rocket according to this invention;

FIG. 2 is a rear elevational view;

FIG. 3 is a right side elevational view of the pyrotechnic rocket, the left side elevation being a mirror image thereof;

FIG. 4 is a top plan view thereof; and,

FIG. 5 is a bottom plan view thereof.
